UNITED STATES PATENT OFFICE.

CHARLES J. HENDRICKSON, OF NEW YORK, N. Y., ASSIGNOR TO WESTERN ELECTRIC COMPANY, INCORPORATED, OF NEW YORK, N. Y., A CORPORATION OF NEW YORK.

AUTOMATIC SWITCH.

1,284,672.

Specification of Letters Patent. Patented Nov. 12, 1918.

Application filed December 29, 1916. Serial No. 139,534.

To all whom it may concern:

Be it known that I, CHARLES J. HENDRICKSON, a citizen of the United States, residing at New York, in the county of New York and State of New York, have invented certain new and useful Improvements in Automatic Switches, of which the following is a full, clear, concise, and exact description.

This invention relates to switches for use 10 in automatic telephone systems, and more particularly to switches in which the power for imparting motion to the brushes is supplied by the action of a plunger and a solenoid.

15 This application is a continuation in part of applicant's copending application, Serial No. 105,355, filed June 23, 1916.

It is the object of the present invention to provide an automatic switch which shall be 20 simple in structure and rapid and accurate in operation.

A feature of the invention is an arrangement by which a solenoid operated switch may be advanced in response to the operation 25 of an impulse sending device.

A further feature of the invention is the use of solenoids to operate a two-motion switch which may be either of the "up-and-around" or the "around-and-up" type.

30 It is thought that the invention will best be understood from the following detailed description, reference being had to the accompanying drawings.

In the drawings, Figure 1 is a side elevation of a selector switch of the "around-and-up" type; Fig. 2 is a view of the lower part of the same, looking from the line 2-2 of Fig. 1; Fig. 3 is a top plan view of a portion 40 of the switch shown in Fig. 1, looking down from the line 3-3 of Fig. 1; and Fig. 4 is a top plan view of a portion of the switch shown in Fig. 1, looking down from the line 4-4 of Fig. 1.

The structure of the switch disclosed in 45 the accompanying drawings will first be described, and will be followed by a description of the operation of such parts of the device as are necessary to an understanding of the invention.

50 A brush-carrying shaft 5 is rotatably and slidably mounted in any desired manner. A plurality of spirally disposed brushes 6 are secured to shaft 5 and are arranged to be brought into operative relation with the various groups of terminals 7 upon rotation of

shaft 5. The arrangement of brushes 6 with respect to the terminal banks 7 is substantially the same as that disclosed in a patent to O. F. Forsberg, No. 1,252,420, issued January 8, 1918.

To the lower portion of shaft 1 is secured a cylinder 8 having a series of notches 9 cut in its surface. Immediately below the cylinder 8 is a magnetic plunger 10 arranged to be attracted by a solenoid 11, the cylinder 8 and plunger 10 being arranged to pass through a cylindrical opening in the center of the solenoid. The solenoid 11 is arranged to give vertical movement to shaft 5, this vertical motion being controlled by means of a frame 12. The frame 12 is pivoted on pins 13 mounted on solenoid 11 and carries at one end an armature 14, and at the other end a pawl 15, the relation of the armature and pawl being best seen in Fig. 4.

A pinion 16 is secured to shaft 5 at some point below the plunger 10 and is in engagement with a strip of toothed rack 17. The toothed rack 17 is mounted on a member 18, which is provided with a series of ratchet teeth 19. Also mounted on the member 18 is a cylinder of non-magnetic material having notches 20 cut in its surface. Fixed to one end of the notched cylinder is a plunger 21 of magnetic material. A solenoid 22 is provided with a central opening through which the cylinder and plunger may pass. Upon energization of solenoid 22 the plunger 21 will be attracted to move rack 17 and cause the rotation of shaft 5 through the action of pinion 16, this motion being controlled by means of a frame 23. The frame 23 is pivotally and slidably mounted on pins 24 secured to the solenoid 22, and carries at one end a pawl 25 of non-magnetic material, and at the other end an armature 26, the relation of pawl 25 and armature 26 being best seen in Fig. 2. Springs 26 and 27 return frame 23 to its normal position when the solenoid 22 is not energized.

The rack 17 is maintained in its operated position against the tension of a restoring spring (not shown) by the action of a holding pawl 28 pressed into engagement with teeth 19 by the action of spring 29.

The pawl 15 holds the shaft 5 in its elevated position by engaging one of the slots 9.

The release of the switch is accomplished by means of a release magnet 30. Magnet 30, by attracting its armature 31, causes an

110

extension 32 to operate pawl 28 by means of a pin 33 to disengage such pawl from one of the notches 19. Armature 31, in moving to the right, slides up a cam surface 34, as best seen in Fig. 4, and causes the frame 12 to rotate about its pivots 13 and withdraw pawl 15 from engagement with one of the notches 9, which allows brush shaft 5 to be restored to its normal vertical position by 10 gravity.

Assuming that the device is to be used as a selector switch, its operation will be as follows: No circuit arrangement has been disclosed, but a suitable circuit arrangement 15 would be of sufficient similarity to that disclosed in a patent to C. L. Goodrum, No. 1,251,503, issued January 1, 1918, as to be unnecessary of detailed description, the chief distinction being that in the present 20 case solenoids would be substituted for stepping magnets, and no means would be necessary for interrupting the circuit of the secondary solenoid.

Upon the receipt of a series of directive 25 impulses, solenoid 22 is intermittently energized and deenergized to attract the plunger 21 and rotate shaft 5 a desired number of steps to bring a brush 6 into operative 30 relation with a group of terminals 7, in which terminate trunks leading to switches of a desired designation.

Upon the first energization of solenoid 22 and before the plunger 21 can move, due to the inertia of the mechanism operated there- 35 by, armature 26 will be attracted, causing the frame 23 to rotate about its pivots, thereby throwing pawl 25 into engagement with the first slot 20. The plunger 21 is then advanced and moves frame 23 to the right with 40 it, since pawl 25 is engaging a slot 20. The forward motion of rack 17 is limited to one step, since the engagement of armature 26 with the body of the solenoid limits the extent of motion.

Upon the first deenergization of solenoid 45 22 armature 26 is retracted by spring 37, thereby disengaging pawl 25 from the first slot 20 and allowing the frame 23 to be returned to its normal position by spring 36. The pawl 25 now lies in the plane of the 50 second slot 20. The rack 17 will be held in its advanced position, since pawl 28 now engages the second ratchet tooth 19. In this 55 way the brush shaft 5 may be rotated a desired number of steps by the action of solenoid 22 in response to the series of directive impulses.

Upon completion of the sending of directive 60 impulses, current will be supplied to solenoid 11 to elevate the brush shaft 5 and cause a positioned brush to hunt over a selected group in search of an idle trunk. Upon energization of solenoid 11 armature 14 is attracted, causing the rotation of frame 65 12, which results in the disengagement of

pawl 15 from the first slot 9. The solenoid 11 is maintained energized until an idle trunk is found, at which time its circuit will be broken. Upon deenergization of magnet 11, armature 14 is retracted by the movement 70 of frame 12 in response to the action of a spring 35, and pawl 15 will engage a slot 9 to hold the shaft in its elevated position.

When connection is no longer desired, magnet 30 is energized and causes the release 75 of the switch, as previously described.

If the invention is to be applied to a selector switch of the up-and-around type, it would only be necessary to provide a solenoid controlled in the same manner as that described for solenoid 22 to produce vertical motion of the shaft, after which the shaft would be rotated by means of a rack and pinion through the action of a solenoid 80 equipped with a controlling device similar 85 to that described for solenoid 11.

If the switch is to be used as a connector; that is, if motion in both directions is to be made responsive to impulse control, then both of the operating solenoids would have 90 to be equipped with controlling mechanism similar to that described for solenoid 22.

What is claimed is:

1. In an automatic switch, a brush carrying shaft, a solenoid and a plunger therefor 95 arranged to impart motion to said shaft, and an armature mounted independently of said plunger and operated by the magnetic field of the solenoid to render the motion of said shaft of a step-by-step character. 100

2. In an automatic switch, a brush-carrying shaft, means, including a plunger and an operating solenoid therefor, for imparting motion to the shaft, and means including a member pivotally and slidably mounted 105 in operative relation to said solenoid to render the motion of the shaft responsive to impulse control.

3. In an automatic switch, a brush-carrying shaft, a solenoid, a plunger for said solenoid operatively connected to said shaft, a series of stops, an armature in operative relation to said solenoid, a pawl carried by said armature and arranged to engage one of said stops upon energization of said solenoid to limit the extent of movement of said switch. 115

4. In an automatic switch, a brush carrying shaft, a solenoid, a plunger rod for said solenoid operatively connected to said shaft, a series of slots in said plunger rod, an arm arranged to engage one of said slots and be moved therewith upon each energization of said solenoid, a stop to limit the extent of movement of said arm, and 120 means to return said arm to its normal position upon each deenergization of said solenoid. 125

5. In an automatic switch, a brush carrying shaft, a solenoid, a plunger rod for said 130

- 5 solenoid operatively connected to said shaft, a series of slots in said plunger rod, an arm arranged to engage one of said slots and be moved therewith upon each energization of 5 said solenoid, a stop to limit the extent of movement of said arm, means to return said arm to its normal position upon each de-energization of said solenoid, and ratchet and pawl mechanism to maintain said brush 10 shaft in an advanced position.
6. In an automatic switch a brush-carrying shaft, means, including a plunger rod and an operating solenoid therefor, for imparting motion to the shaft, a series of 15 notches on said rod, a pawl arranged to engage said notches, a series of slots in said rod, an arm to engage said slots, and a frame pivotally and slidably mounted on said sole- 20 noid, said arm being carried by said frame, said elements constituting means to render the motion of the shaft responsive to impulse control.
7. In an automatic switch, a brush-carrying shaft arranged to be moved in a plurality of directions, and a plurality of sole- 25 noids and plungers therefor arranged to cause such motions of said shaft.
8. In an automatic switch, a brush-carrying shaft arranged to be moved in a plurality of directions, operating solenoids and 30 plungers therefor, and means to render motion of said brush shaft subject to impulse control.
9. In an automatic switch, a brush-carrying shaft mounted so as to be capable of 35 both rotary and vertical motions, a plunger on said shaft and an operating solenoid therefor, a pinion on said shaft, a rack en-gaging said pinion and carrying a plunger, 40 and a solenoid for operating said plunger.
10. In an automatic switch, a brush-carrying shaft mounted so as to be capable of 1 both rotary and vertical motions, a plunger on said shaft, an operating solenoid there- 45 for, a pinion on said shaft, a rack engaging said pinion and carrying a plunger, a sole- 50 noid for operating said plunger, and means to render motion in one direction subject to impulse control.
- 50 11. In an automatic switch, a brush carrying shaft, a solenoid, a plunger for said
- 55 solenoid arranged to impart motion to the brush shaft, and an armature for said sole- 60 noid, said plunger and armature coöperat- 65 ing with each other to render the motion of 65 said shaft responsive to impulse control.
12. In an automatic switch, a brush car- 70 rying shaft, a solenoid, a plunger therefor arranged to impart motion to the brush shaft, and an armature for said solenoid, 70 said plunger and armature being simultane- 75 ously responsive to the energization of said solenoid to render the motion of the brush shaft subject to impulse control.
13. In an automatic switch, a brush car- 80 rying shaft, a solenoid, a plunger therefor for moving said brush shaft, and an armature for said solenoid mounted for movement in two directions, said armature being mov- 85 able in one direction in response to the energization of the solenoid and movable in the other direction in response to the movement of said plunger to thereby limit the extent of motion of said brush shaft.
14. In an automatic switch, a brush car- 90 rying shaft, a solenoid, a plunger rod there- 90 for for moving said shaft, a series of stops on said plunger rod, and an armature for said solenoid mounted in operative relation thereto and having a pawl thereon arranged to coöperate with said stops, said plunger being responsive to the energization of the sole- 95 noid to advance the brush shaft, said armature being movable in response to the energization of the solenoid to engage said pawl with one of said stops, said armature being further movable in response to movement of the plunger rod to limit the extent of motion of the brush shaft for each energization of the solenoid.
15. In an automatic switch, a brush shaft, a solenoid, a plunger therefor operatively connected to said shaft, and an armature for said solenoid, said plunger and armature being responsive to successive energizations of 95 said solenoid and arranged to coöperate with each other to impart successive movements of equal extent to said brush shaft.

In witness whereof, I hereunto subscribe my name this 28th day of December A. D., 1916.

CHARLES J. HENDRICKSON.
